UNITED STATES PATENT OFFICE

WILLIAM HENRY CHAPMAN, OF PORTLAND, MAINE, ASSIGNOR TO CHAPMAN ELECTRIC
NEUTRALIZER COMPANY, OF PORTLAND, MAINE, A CORPORATION OF MAINE

DISCHARGE BAR FOR NEUTRALIZING STATIC ELECTRICITY

Application filed April 6, 1929. Serial No. 353,219.

My present invention relates to certain improvements in discharge bars of systems for neutralizing static electricity generated in the process of manufacture or the printing of paper textile fabrics or the like, whereby the static charge on these materials is neutralized by the discharge upon them of high voltage alternating charge through the air.

Under many operating conditions these bars are apt to become coated by dusty escapements from the materials being used whereby the efficiency of the apparatus is decreased. As a characteristic instance which has caused much difficulty, and in fact seemed previously to have precluded the satisfactory use of neutralizers, I cite the instance of printing where a metallic powder is employed.

The use of bronze powder has been particularly troublesome as this powder collects on the distributor bar. All other neutralizer bars that have ever been produced heretofore are weakened in their useful activity by the deposit of bronze powder upon them due to the fact that the bronze coated surfaces form an avenue of escape for the charge that should be allowed to escape only at the discharge points.

Any deposit of bronze powder on my new bar virtually increases the surface of the inductive sleeves adding an extra charge which can only escape through the discharge points and makes them all the more active, while at the same time the inducing charge on the rod is prevented from escaping by its dust tight enclosure. This dust or powder furthermore was very penetrating and worked its way into the crevices between the various parts and could only be removed with considerable difficulty and at considerable expense.

Furthermore, the protection of the bar connections proved difficult under such conditions, as these connections usually had to be of certain length because the bar itself is necessarily disposed closely adjacent the travelled sheet and therefore at some distance from the current source.

Furthermore, a common difficulty in the mounting of the discharge points has been

in getting them tightly mounted in proper spacing along the distributor bar.

In addition to the foregoing, the actual discharge points if unprotected were apt to be bent or broken. To prevent this I have for certain instances provided guards, but these guards while successful under certain conditions introduced disturbing factors and in such a case as that cited where metallic dust deposited, these guards becoming coated, interfered with the localization of the discharge at the discharge point, which in practice is required to be a very fine point.

The foregoing difficulties have been overcome by me in accordance with my present invention, which I will now describe in detail, although I do not wish to be limited thereby except as I shall so indicate.

As illustrative of my invention, I have shown in the accompanying drawings, apparatus in accordance with the principles thereof and a simple and highly efficient type well adapted to a great variety of usages and capable of production at very reasonable cost.

Throughout the specification and drawings like reference characters are employed to indicate corresponding parts, and in the drawings:

Fig. 1 is a general view of a bar installation.

Fig. 2 is a fragmentary view of a bar in accordance with my invention partly sectioned to indicate the construction thereof.

Fig. 3 is a partial section through the discharge point holder.

Fig. 4 is a section on the line 4—4, of Fig. 1.

Figs. 5 and 6 are respectively a side and plan view of a modified form of point.

I have indicated at B a rod or bar preferably a rigid conductor member for which purpose I may use a steel rod of the desired diameter and adapted to be electrically connected to an alternating current generator G and transformer T having a high tension secondary coil S one end of which is connected to the cable E leading to the neutralizer bar B and the other end to the ground X.

Suitable supports are provided for the bar as indicated by the hangers J which are pref-

erably made of wood or fibre, preferably suspended from the ceiling or at some point sufficiently distant to be beyond the range of the flying dust, and are provided at their lower ends with clamp members K of like material, adapted to hold the bar.

Over the bar I place an envelope A preferably in the form of an insulating tube. This preferably fits the bar B snugly and is preferably slightly elastic and compressible and should also be reasonably flexible for reasons which I will later explain. For this purpose a rubber or composite tube as of rubber and fabric may be employed. As shown it should be of such length as to extend up over the conductor cable E, and as such cable is usually bent adjacent the bar, the matter of flexibility is one of great convenience. At the opposite end of the bar B the tubular sheathing extends for a short distance and receives an insulating plug D of rubber or hard fibre to which the end of the tubing is tightly clamped as by a clamp C in order to get a perfectly dust tight joint and to hold the parts contained snugly in place.

At the conductor end the cable E enters the tube A. This cable preferably snugly fits the bore of the tube A or is made to do so so that it can be clamped by a clamp C to make it a perfectly dust proof joint. The end of the cable E is provided with a spring F for making contact with the end of the bar B, the parts being assembled under such compression of the spring as will insure contact at all times and take up any expansion or contraction or compensate for any adjustment or movement made if the connections are flexed.

Over the tube A and spaced along the bar B I arrange my discharge members. Of these I have shown two characteristic types. For installations involving, for example, the metallic dust, I prefer a discharge member shown in the sectional view, Fig. 3. In this I provide an inductor band or strap I having a pair of ears i apertured to receive the shank of a bolt-like member M. The shank of this member is threaded to receive a tubular member N which has a threaded portion adapted to receive the bolt shank locked by nut N¹ and a reduced bore leading therefrom to its opposite end. This member carries the discharge point P which is preferably formed of wire, its base being wound in a conic spiral coil P¹ formed with an enlarged base portion P² adapted to be clamped in a larger portion of the bore by the end of the bolt shank. This makes possible a very tight joint and an advantageous support for the point at its outer end. The bore of the member N is flared out as indicated at n so as to permit a free flexation of the portion P¹ of the point.

The point P if accidentally struck will therefore yield resiliently but will spring

back in place and as the point is made of rather fine wire it can be, if actually bent, readily straightened out. As indicated, such a point usually lies parallel with the run of the paper as indicated in Fig. 4 and pointing in the direction of movement of the paper. The points, however, may be readily adjusted by simply loosening the bolt member M and slipping the band on the envelope A. It will be noted that these point clamps can be set up tightly owing to the compressibility of the envelope A so that when once adjusted they tend to hold in place both on account of the tightness of their clamping and also due to their slight embedding in the surface of the envelope A.

In the form shown in Figs. 5 and 6 I form the inductor strap J with one end projecting farther than the other to form a point R. Over these I place a pair of guards Q of insulating material beveled off on their inner faces as at q and held by a bolt S. This type of point I find very satisfactory except in the presence of dust as before indicated.

As hereinbefore stated, the devices shown are illustrative but they do represent very practical and convenient apparatus. Such structure, however, may be variously modified and variously combined and various materials used or substituted, and all without departing from the spirit of my invention as defined in the following claims.

What I therefore claim and desire to secure by Letters Patent is:—

1. A discharge bar for neutralizing static electricity comprising a conductor member, an electrical connection therefor, a compressible insulating sheath thereon and compressibly adjustable discharge members mounted on said sheath.

2. A discharge bar for neutralizing static electricity comprising a rigid conductor member, an electrical connection therefor, a compressible insulating sheath thereon and compressibly adjustable discharge members mounted on said sheath.

3. A discharge member for a static neutralizer comprising a tubular holder having an enlarged and threaded bore at one end, a wound point member comprising a conic spiral part having an enlarged base and a free apex point, said base being lodged in said enlarged bore, and a threaded member compressibly engaging said enlarged end.

4. A holder for the discharge point of a static neutralizer, said discharge point having an enlargement constituting a base comprising a tubular member having an enlarged and threaded bore at one end and a flaring mouth at the other, and a threaded member entered in said enlarged bore and adapted to compressibly clamp the base of a discharge point lodged in said tubular member.

5. A discharge bar for neutralizing static

electricity comprising a conductor bar, a compressible insulating sheath thereon, a capacitively coupled sleeve, means for clamping it about the bar, and a resiliently mounted discharge point connected to said sleeve and comprising a conic spirally coiled base and a tip member projecting therefrom.

5 6. A capacitively coupled discharge member for a neutralizer bar comprising a sleeve of conducting material, means for clamping it about the bar, and a discharge point having a conic spirally coiled base connected to said sleeve and a tip member projecting therefrom.

10 15 In testimony whereof I affix my signature.
WILLIAM HENRY CHAPMAN.
